UNITED STATES PATENT OFFICE.

JOHN J. FRANK, OF SCHENECTADY, NEW YORK, ASSIGNOR TO GENERAL ELECTRIC COMPANY, A CORPORATION OF NEW YORK.

THREE-PHASE TRANSFORMER.

No. 853,778.

Specification of Letters Patent.

Patented May 14, 1907.

Application filed September 19, 1906. Serial No. 335,213.

To all whom it may concern:

Be it known that I, JOHN J. FRANK, a citizen of the United States, residing at Schenectady, county of Schenectady, State of New York, have invented certain new and useful Improvements in Three-Phase Transformers, of which the following is a specification.

My invention relates to three-phase transformers of the "shell" type, and its object is to provide a novel construction which will permit the use in oil-cooled transformers of a tank or casing circular in cross-section, without employing an unnecessarily large amount of oil. The use of round tanks is particularly desirable where forced circulation of oil is employed and the oil in the transformer is therefore under considerable pressure, since under these circumstances a tank which is not circular in cross-section is apt to become distorted from the oil-pressure.

In the construction of three-phase "shell" type transformers it has ordinarily been the practice heretofore to arrange the three windings with their axes in alinement. With this arrangement of windings the core is considerably longer than broad, so that a tank of circular cross-section cannot be used without an unnecessarily large amount of oil.

My invention consists in placing one of the three windings with its axis perpendicular to the line joining the centers of the other two windings. I thereby obtain a core which is much more nearly square than the usual construction, so that a circular tank may be used with a much smaller amount of oil.

My invention will best be understood by reference to the accompanying drawings, in which

Figure 1 shows a plan view of a transformer arranged in accordance with my invention; and Fig. 2 shows an elevation of the same with the casing removed.

In the drawings, A represents the transformer-core, which is constructed of laminations in the usual manner, and which is pro-

vided with apertures in which the windings B¹, B² and B³ for the three phases are arranged. The windings B¹ and B² may be arranged in the usual manner with their axes in alinement, but the winding B³ is placed with its axis at right-angles to the other two, and midway between the other two windings. This arrangement, as is evident in Fig. 1, gives a core construction which is much more nearly square than would be the case if the third winding were placed with its axis in alinement with the other two, as in the usual construction. Consequently, a circular tank or casing C may be employed without an unnecessarily large amount of oil.

What I claim as new and desire to secure by Letters Patent of the United States, is,—

1. A three-phase transformer of the "shell" type comprising a magnetic core, and three windings arranged in apertures in said core, one winding having its axis perpendicular to the line joining the centers of the other two windings.

2. A three-phase transformer of the "shell" type comprising a magnetic core, three windings arranged in apertures in said core, one winding having its axis perpendicular to the line joining the centers of the other windings, and a casing of circular cross-section adapted to contain said core.

3. A three-phase transformer of the "shell" type comprising a magnetic core, and three windings arranged in apertures in said core, two of said windings being axially-aligned and the third having its axis perpendicular to the axis of the other two.

4. A three-phase transformer of the "shell" type comprising a magnetic core, three windings arranged in apertures in said core, two of said windings being axially-aligned and the third having its axis perpendicular to the axis of the other two, and a casing of circular cross-section adapted to contain said core.

5. A three-phase transformer of the "shell" type comprising a magnetic core, and three windings arranged in apertures in said core, one winding having its axis perpen-

dicular to the line joining the centers of the other two windings and midway between them.

6. A three - phase transformer of the "shell" type comprising a magnetic core, and three windings arranged in apertures in said core, two of said windings being axially-alined and the third having its axis perpen-

dicular to the axis of the other two and midway between the other two windings.

In witness whereof, I have hereunto set my hand this 17th day of September, 1906.

JOHN J. FRANK.
